UNITED STATES PATENT OFFICE.

JAMES K. COCHRAN, OF CHICAGO, ILLINOIS.

SELF-PROPELLED CAR-TRUCK.

No. 841,983.

Specification of Letters Patent.

Patented Jan. 23, 1907.

Application filed August 9, 1906. Serial No. 329,910.

To all whom it may concern:

Be it known that I, JAMES K. COCHRAN, a citizen of the United States, residing at Chicago, in the county of Cook and State of Illinois, have invented a new and useful Self-Propelled Car-Truck, of which the following is a specification.

This invention relates more particularly to improvements in self-propelled trucks for railway-cars.

One of the principal objects of the present invention is to produce a motor-car truck wherein the motor, though yieldingly mounted, is carried more directly by the wheels driven thereby, so that the relative movement is comparatively slight and intricate mechanism to allow for great relative movement is thus unnecessary.

Another object is to mount the car-body or body-supporting truck frame or bolster so that the usual vibrations and movements of such body and frame carrying it will be largely independent of the motor and will not affect the latter.

A still further and important object is to provide, in connection with the above, novel driving mechanism whereby transmission of power from the motor to the wheels is secured and all wheels of the truck driven, the speed thereof being easily regulated without altering the speed of the motor.

The preferred form of construction is illustrated in the accompanying drawings, wherein—

Figure 1 is a plan view of a railway-car motor-truck. Fig. 2 is a side elevation of the same. Fig. 3 is a longitudinal sectional view therethrough. Fig. 4 is a cross-sectional view on the line 4-4 of Fig. 3. Fig. 5 is a cross-sectional view on the line 5-5 of Fig. 3. Fig. 6 is a detail view showing one of the eccentrics for adjusting one of the friction-wheels. Fig. 7 is a similar view of one of the eccentrics for adjusting the associated friction-wheel. Fig. 8 is a cross-sectional view on the line 8-8 of Fig. 4. Fig. 9 is a plan view of the means for effecting the adjustment of the friction-wheels radially of the driving-disks.

Similar reference-numerals designate corresponding parts in all the figures of the drawings.

In the embodiment illustrated spaced axles 10 are employed, to which are secured the usual wheels 11, all of which constitute trac-

tion-wheels. These axles are provided at their ends with journal-boxes 12, and mounted thereon in any suitable manner is the main truck-frame. Thus in the disclosed form of construction inner and outer hanger-links 13 are suspended from each box, and plates 14, bridging the spaces between the lower ends of each set of hanger-links, constitute supports for springs 15. A main frame is employed comprising bars 16, connected at their ends by cross-bars, the side bars having plates 18, that bear upon the springs 15, so that said main frame is yieldingly suspended from the journal-boxes.

The above-described main frame is provided between the side bars with a motor-supporting or sub frame comprising transoms 17, on which are mounted spaced longitudinally-disposed stringers 19, that have free outer ends raised above the planes of the main portions of said stringers. The said ends are connected by trusses 20.

A driving-motor is mounted centrally of the subframe and consists of a central longitudinally-disposed driving or crank shaft 21, surrounded by a central casing 22, on opposite sides of which extend a plurality of motor-cylinders 23, six being shown, though more or less may be employed, as desired. The driving-shaft 21 extends on opposite sides of the motor. To both ends of said shaft are fixed sets of spaced friction driving-disks 24, the disks of each set having inner opposed friction-faces 25. Two counter-shafts 26 are located between the driving-disks 24 of each set transversely of the same, and each counter-shaft is journaled in a pair of eccentrics 27, the eccentrics of one shaft being disposed in opposite relation to those of the other shaft, as will be clear by reference to Figs. 5, 6, and 7. The eccentrics for the outer ends of the shafts are journaled in the depending portions of the trusses 20, while the eccentrics for the inner ends of said shafts are journaled in hanger-bearings 28, through which the driving-shaft 21 passes, as clearly shown in Fig. 5, the said hangers being suspended from the central portions of the trusses 20. The outer ends of the counter-shafts 26 are provided with sprocket-wheels 30, around which pass sprocket-chains 31, that also pass around other sprocket-wheels 32, connected to the axles 10 just inside the traction-wheels 11. Slidably mounted on the counter-shafts 20, but suitably held against

rotation thereon, are friction-wheels 33, that operate between the adjacent driving-disks 24 and coöperate with their inner surfaces 25.

While the means for adjusting the friction-wheels may be of any desired character, the mechanism preferably employed is as follows: The eccentrics for each counter-shaft are provided with depending arms 34, connected at their lower ends by cross-rods 35, so that they may be moved in unison. The cross-rod of each set at one end of the motor is connected to the cross-rod of the corresponding set at the other end of the motor by a link 36. By this arrangement it will be apparent that if the links 36 are moved longitudinally in unison by any suitable means the counter-shafts 26 will be moved laterally in opposite directions, and thus each friction-wheel will be brought into engagement with one of the friction-surfaces 25 of the driving-disks 24. Therefore if the driving-shaft 21 is in operation power will be transmitted through the driving-disks 24 and friction-wheels 33 to the counter-shafts and thence through the chain-gearing to the traction-wheels. These counter-shafts will always rotate in the same direction, and inasmuch as the motor is thus connected to all the wheels of the truck, or, in other words, has a plurality of connections with each axle, the greatest amount of power will be transmitted without any undue strain on any particular part and all the wheels of the truck will be driven in unison.

The speed of the traction-wheels 11 can of course be varied by moving the friction-wheels 33 toward and from the shaft 21. To accomplish these movements, the following mechanism is preferably employed: By referring to Fig. 8 it will be observed that the trusses 20 have depending and inturned flanges 37, forming guideways in which are mounted reciprocating rack-bars 38. These rack-bars are in mesh with pinions 39, located between them, and said rack-bars carry on opposite sides of the pinions depending arms 40, provided with yokes 41, that engage in annular grooves 42, formed in the hubs of the friction-wheels 33. One of the racks of each truss is extended beyond the other and meshes with a pinion 43, said pinion being connected to another pinion 44, located beneath the same. An actuating-bar 45, extending transversely of the bars 38 and longitudinally of the truck, has sliding bearings 46 in the trusses and is provided with racks meshing with the pinions 44. It will thus be evident that if the bar 45 is moved in one direction or the other the pinions 44 and 43 will be rotated, thus carrying the racks 38 in opposite directions and moving the friction-wheels 33 toward and from the driving-shaft.

As already shown, the above-described motor and driving-gears are carried by the sub or motor-supporting frame. The body

of the car is supported on another frame and bolster arranged thereover and designated as a whole by the reference-numeral 47. This frame is a distinct frame from the main and motor-supporting frames, but is yieldingly mounted thereon and carried thereby. To this end telescoping guide-casings 48 are carried by the two frames and inclose springs 49, interposed between said frames. The body-supporting frame furthermore has depending pedestals 50, which embrace and are slidable upon the journal-boxes 12. The advantages of this construction will be obvious. The motor and gearing are supported directly from the wheel-base and while yieldingly mounted the relative movement will be comparatively small, so that no intricate gear connections between the friction-drive and traction wheels or axles is necessary. On the other hand, the body-supporting frame and bolster are mounted on the main frame and are capable of movement entirely independent thereof, so that the jar and sway of the body will not materially affect the motor-frame, and consequently the motor and its associated parts. There are thus two features of great importance in the present case—namely, the supporting of the motor and drive-gearing, so that the movement of the body will not disturb it in its relation to the axles and traction-wheels, and the arrangement and construction of said drive-gearing so that the full power will be transmitted to all the wheels of the truck and the weight of the mechanism will be properly distributed upon the truck.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a self-propelled car-truck, the combination with traction-wheels, and axles, of a main frame supported thereon, a subframe carried by the main frame, a motor mounted on the subframe and having a driving-shaft projecting beyond its opposite sides, a plurality of friction drive-disks mounted on each end of the shaft, and a plurality of friction devices associated with the disks and having driving connections with the adjacent shaft and wheel.

2. In a self-propelled car-truck, the combination with a main frame, of axles, and traction-wheels supporting the same, a body-supporting frame yieldingly mounted on the main frame, a subframe carried by the main

frame, a motor arranged on the subframe and having a driving-shaft extending on both sides thereof, a plurality of opposing disks mounted on each end of the driving-shaft and

5 having inner friction-surfaces, a plurality of counter-shafts located between each set of opposing disks, a plurality of driving connections between the counter-shafts and the adjacent axle and wheels, friction-wheels 10 slidably mounted on the counter-shafts, and means for moving said counter-shafts laterally and for moving the wheels longitudinally of the counter-shafts.

3. In a self-propelled car-truck, the combination with axles and traction-wheels 15 mounted thereon, of journal-boxes for the axles, hanger-links suspended from the journal-boxes, springs located in the hanger-links, a main frame mounted on the springs, 20 a sub or motor frame carried by said main frame, springs mounted on the main frame, a body-supporting frame mounted on the latter springs, pedestals carried by the motor-supporting frame and slidably engaging the 25 journal-boxes, a motor mounted on the sub or motor frame, and including a driving-shaft extending on opposite sides of said motor, and gearing connecting the opposite ends of the driving-shaft to the axles and 30 traction-wheels, said gearing being carried by the motor-supporting frame.

4. In self-propelled car-truck, the combination with spaced sets of spaced wheels, of a motor located between the sets and having 35 a driving-shaft projecting beyond its opposite sides, sets of spaced and opposed friction-faced driving-disks mounted on the driving-shaft on opposite sides of the motor, a plurality of counter-shafts located between the 40 faces of the different sets of driving-disks and having friction-wheels co-operating therewith, and connections between the counter-shafts and the adjacent sets of traction-wheels.

5. In a self-propelled car-truck, the combination with front and rear sets of wheels, of a motor located between the sets and having 45 a driving-shaft projecting beyond its opposite sides, disks secured to the shaft on opposite sides of the motor, a plurality of 50 separate counter-shafts disposed on each side of the motor and having friction-wheels co-operating with the disks, and a driving connection between each counter-shaft and one of the car-wheels.

55 6. In a self-propelled car-truck, the combination with spaced axles having wheels fixed thereto, of a motor located between the axles and having a shaft disposed transversely thereof, friction mechanism associated with the shaft and located on opposite sides of the motor, each mechanism including counter-shafts having a plurality of driving connections with each adjacent axle and wheel.

65 7. In a self-propelled car-truck, the com-

bination with spaced axles and their wheels, of a motor-supporting frame carried by the axles and projecting beyond the outer sides thereof, a motor mounted centrally of the frame between the axles, said motor including a driving-shaft that projects beyond the axles transversely thereof, and a plurality of cylinders disposed on opposite sides of the motor-shaft, sets of spaced disks carried by the driving-shaft on opposite sides of the 75 motor and having inner opposed friction-surfaces, a plurality of counter-shafts located between each set of disks and having friction-wheels co-operating with the opposed friction-surfaces thereof, and driving connections between the various counter-shafts and the adjacent axles and wheels.

8. In a self-propelled car-truck, the combination with spaced axles, and traction-wheels, of a main frame yieldingly supported 85 thereon, a motor-supporting or sub frame carried by the main frame and including trusses, a motor mounted on the subframe between the trusses and having a driving-shaft extending beyond its opposite sides, oppositely-disposed friction-faced driving-disks mounted on each end of the shaft on opposite sides of the trusses, a hanger-bearing suspended from the central portion of each truss and disposed between the driving-disks, 90 oppositely-disposed eccentrics journaled in the hanger-bearings and in the end portions of the subframe, means connected to the eccentrics for rotating the same, counter-shafts journaled in the eccentrics and having sprocket-wheels on their outer ends, 95 sprocket-gearing between the said sprocket-wheels and the traction-wheels, friction-wheels slidably mounted on the counter-shafts and co-operating with the friction-surfaces of the driving-disks, and means for moving said wheels toward and from the driving-shaft.

9. In a self-propelled car-truck, the combination with traction-wheels, and axles, of 110 a main frame yieldingly supported thereon, a subframe carried by the main frame, a motor mounted on the subframe, a separate friction drive-gearing connection between the motor and each of the wheels, and a body-supporting frame yieldingly mounted on the 115 main frame.

10. In a self-propelled car-truck, the combination with traction-wheels, axles, journal-boxes, and main truck-frame in which said 120 parts are mounted, a subframe arranged within the main frame, a motor carried by the subframe and having a shaft disposed longitudinally of the truck, a friction drive-gearing between the shaft and each of the 125 wheels, and the body-frame arranged above the main frame and subframe and having depending pedestals which embrace and are slidable upon the journal-boxes.

11. In a self-propelled car-truck, the com- 130

- combination with traction-wheels, axles, journal-boxes, springs, and a main truck-frame in which said parts are mounted, of a sub-frame or motor-supporting frame carried by the main frame, a motor mounted on said subframe and having friction drive-gearings connecting with all the wheels, a body-supporting frame independent of the main and sub frames, and telescoping guide-casings with springs for yieldingly supporting the body-frame.
12. In a self-propelled car-truck, the combination with traction-wheels, axles, journal-boxes, and springs, and a main truck-frame in which said parts are mounted,

a subframe mounted on and carried by the main frame and arranged within the latter, friction drive-gearing carried by the subframe at each end and having chain-and-sprocket connections with all the wheels, and a motor carried by the subframe and connecting with the said friction-gearing. 20

In testimony that I claim the foregoing as my own I have hereunto affixed my signature in the presence of two witnesses.

Correction in Letters Patent No. 841,933.

It is hereby certified that in Letters Patent No. 841,933, granted January 22, 1907, upon the application of James K. Cochran, of Chicago, Illinois, for an improvement in "Self-Propelled Car-Trucks," an error appears in the printed specification requiring correction, as follows: In line 125, page 2, the word "wheel" should read *wheels*; and that the said Letters Patent should be read with this correction therein that the same may conform to the record of the case in the Patent Office.

Signed and sealed this 5th day of February, A. D., 1907.

[SEAL.]

F. I. ALLEN,
Commissioner of Patents.

- 1 combination with traction-wheels, axles, journal-boxes, springs, and a main truck-frame in which said parts are mounted, of a sub-frame or motor-supporting frame carried by 5 the main frame, a motor mounted on said subframe and having friction drive - gearings connections with all the wheels, a body-supporting frame independent of the main and sub frames, and telescoping guide-casings 10 with springs for yieldingly supporting the body-frame.
12. In a self-propelled car-truck, the combination with traction-wheels, axles, journal-boxes, and springs, and a main truck-frame in which said parts are mounted, 15

a subframe mounted on and carried by the main frame and arranged within the latter, friction drive-gearing carried by the sub-frame at each end and having chain-and-sprocket connections with all the wheels, and a motor carried by the subframe and connecting with the said friction-gearing. 20

In testimony that I claim the foregoing as my own I have hereunto affixed my signature in the presence of two witnesses.
